UNITED STATES PATENT OFFICE.

JNO. W. RICHARDS, OF NEW YORK, N. Y.

FIRE AND VENTILATING APPARATUS FOR SHIPS.

Specification of Letters Patent No. 22,827, dated February 1, 1859.

To all whom it may concern:

Be it known that I, JOHN W. RICHARDS, of the city, county, and State of New York, have invented a new and improved system 5 of applying pipes for the introduction of air for ventilation and steam for extinguishing fire between the decks, in the holds, and between the timbers of ships and other vessels; and I do hereby declare that the following is a full, clear, and exact description of the same, reference being had to the accompanying drawings, making part of this specification in which—

Figure 1 is a transverse section of a vessel exhibiting my improved system of pipes. Fig. 2 is a longitudinal section of part of the vessel. Figs. 3, 4, 5, 6, 7, and 8 are views of some of the details of the system.

Similar letters of reference indicate corresponding parts in the several figures.

My invention, which is more particularly applicable on board of steam vessels, consists in the employment of a series of pipes having orifices or branches communicating 25 with the spaces between the decks, the cabins, the state rooms, the hold, and the spaces between the timbers, and having separate connections with a blowing apparatus and with a steam-boiler, either of which connections can be opened at pleasure by the engineer or other person qualified or appointed to their control, for the purpose of introducing through said series of pipes a copious supply of fresh air for ventilation 30 till fire occurs in any portion of the vessel, when the air may be shut off from that part and steam admitted thereinto in sufficient quantity to effect its extinction.

It also consists in a certain mode of applying the air and steam pipes so as to afford convenience for the occupants of the several berths to so direct the air supplied to their berths as may be most agreeable, without interfering with the air supplied to 45 other berths.

To enable others to make and use my invention, I will now proceed to describe its construction and operation.

A, is the hull of the vessel.

50 B, B', B², are the decks.

C, is the hold.

D, D, are berth frames on the lower deck.

E, E, are state rooms between the middle and main decks.

55 F, F, F', are the pipes for introducing air or steam into the between-decks and

hold of the vessel; said pipes being arranged in trains along the sides of the vessel in the hold and between the decks, each train extending the whole or any portion of the 60 length thereof. Those of the said pipes which are arranged between decks have numerous orifices a, a, for the issue of air or steam. Those which are in the hold have similar orifices and small branch pipes 65 b, b, leading through the inner planking to the spaces between the timbers. Each train of pipes F, or F', is connected with an air-supply pipe G, communicating from the blowing apparatus, and also a steam-supply pipe H, communicating from the steam-boiler, each of which supply pipes is furnished with a cock c, to close it; or the several steam and air supply pipes may be so connected with two main supply pipes that 70 the air or steam may be let on or shut off by a single air-cock and a single steam-cock in the engine-room or other place convenient of access to the officer in charge of the apparatus.

The pipes in the hold may be fixtures, and so arranged and secured close to the sides or deck as not to interfere with the stowage of cargo. But it may be desirable to have some of the trains of pipes between-decks, or portions thereof, movable so that they can be put up when passengers are to be carried in that part of the ship but taken down when cargo is to be stowed there; and with this end in view I propose in some cases to make the trains of a series of short lengths of pipe g, g, and to connect said lengths together by joint boxes I, I, which drop into suitable supports i, i, secured permanently to the sides of the vessel, as represented in the train F¹, between the decks B, and B'. The ends of the several lengths g, g, of pipe are simply fitted easily into the joint boxes, which partake of the character of journal boxes, and may be made each of a solid piece or casting of metal, or divided longitudinally like journal boxes. The said boxes may be provided at their backs with taper dovetails h, h, as shown in Fig. 5, which is a horizontal section and also in Fig. 8, which is a back view of one of the boxes detached, to drop into corresponding grooves in the supporting plates i, i.

To provide for the convenient stowage of the pipes when taken down, I make the successive lengths, commencing at the steam

and air supply pipes, of gradually diminishing sizes, so that the whole or any number of the pipes of a train may slide into one another as shown in Fig. 6. This gradual diminution of the size of the pipes in the train, besides affording convenience for stowage, is calculated to give a more uniform supply of air or steam from all parts of the train than would be given by a uniform size of pipe; as the first length of the pipe has to convey air or steam for the whole length of the train, the second to convey the whole quantity minus that which is desired to escape from the first, and so on; the last length only requiring to convey enough for its own supply.

The joint boxes I, I, to receive the pipes of diminishing sizes, are made with one-half of the interior of a size to receive the larger and the other half of a size to receive the smaller of the pipes which they are to connect, and with a small internal flange *d*, as shown in the vertical sectional view, Fig. 3, and the horizontal section, Fig. 4, to prevent the smaller pipe slipping into the larger one and thus breaking its connection with the next smaller one. The joint boxes may be mere rough castings, as tight joints are not required, for the air or steam may as well issue from the joints as from the orifices *a*, *a*.

It will be convenient when the trains of pipe pass through the sleeping berths to have the lengths *g*, *g*, to correspond with the lengths of the berths, as shown in Fig. 2, so that the occupant of any berth can, without interfering with the supply of air at any other part of the same train, turn the pipe therein to direct toward or away from him the streams of air issuing from the orifices *a*,

if said orifices are all on one side of the pipe; and to permit this I intend always to have the pipes fit the joint boxes loosely enough to be capable of turning easily therein.

J, J, are trains of pipes for conveying air to the state rooms E, E; said pipes being secured permanently below the deck B', and intended to have connected with them, air and steam supply pipes like the trains of pipes before described; and having small branches *e*, *e*, passing up through the decks into the state rooms; the said branches being fitted with perforated caps *f*, *f*, which can be raised or lowered to regulate the supply of air for ventilation. One of these branch pipes *e*, *e*, and caps *f*, *f*, is shown in section in Fig. 7.

What I claim as my invention, and desire to secure by Letters Patent, is:

1. Arranging and applying the pipes F, F', J, or their equivalents leading to the different parts of the vessel, in combination with suitable connections with a boiler and a blower or air-forcing apparatus, that the said pipes may be used as required to supply either air for ventilation or steam for the extinction of fire, substantially as herein described.

2. Applying the several lengths of pipe in a train that they are capable of being turned in their joint-boxes or supports, for the purpose of giving such direction to the ventilating air supplied by each length as the occupants of the berth or part of the vessel supplied by it may desire, as herein described.

JOHN W. RICHARDS.
